US0D1103799S

(12) **United States Design Patent** (10) **Patent No.:** **US D1,103,799 S**
(45) **Date of Patent:** **** Dec. 2, 2025**

(54) **ANALYZER DEVICE**

(71) Applicant: **Rigaku Analytical Devices, Inc.**,
Wilmington, MA (US)

(72) Inventors: **Michael Damento**, Tucson, AZ (US);
Kenneth Vachon, Holliston, MA (US)

(73) Assignee: **RIGAKU AMERICAS HOLDING,
INC.**, Wilmington, MA (US)

(**) Term: **15 Years**

(21) Appl. No.: **29/935,544**

(22) Filed: **Apr. 2, 2024**

(51) LOC (15) Cl. **10-04**

(52) U.S. Cl.

(57) **CLAIM**

The ornamental design for an analyzer device, as shown and described.

DESCRIPTION

FIG. 1 is a first isometric view of an embodiment of an analyzer device, showing our new design;

FIG. 2 is a second isometric view thereof;

FIG. 3 is a top plan view thereof;

FIG. 4 is a bottom plan view thereof;

FIG. 5 is a first side elevational view thereof;

FIG. 6 is a second side elevational view thereof;

FIG. 7 is a first end elevational view thereof; and,

FIG. 8 is a second end elevational view thereof.

1 Claim, 6 Drawing Sheets
